DISPOSABLE FIBER TIP MARKER

William R. Dahl, Lakewood, Colo., assignor to
Honeywell Inc., Minneapolis, Minn.

Filed Sept. 14, 1971, Ser. No. 180,537

Term of patent 14 years

Int. Cl. D19—06

U.S. Cl. D74—17 B

FIG. 1

FIG. 2

FIG. 1 is a side elevational view of a disposable fiber tip marker showing my new design; and

FIG. 2 is a bottom plan view thereof.

The front, top and rear surfaces of the marker are flat and the side opposite to that of FIG. 1 is substantially a mirror image thereof.

I claim:

The ornamental design for a disposable fiber tip marker, as shown and described.
